UNITED STATES PATENT OFFICE.

CHARLES F. L. KAUFMANN AND WALLER L. KAUFMANN, OF SANTA ANA, CALIFORNIA.

DESIGN FOR A SPOT-LIGHT HANDLE-STEM.

57,056.

Specification for Design.

Patented Feb. 1, 1921.

Application filed January 13, 1920. Serial No. 351,280. Term of patent 14 years.

To all whom it may concern:

Be it known that we, CHARLES F. L. KAUFMANN and WALLER L. KAUFMANN, citizens of the United States, residing at Santa Ana, in the county of Orange and State of California, have invented a new, original, and ornamental Design for a Spot-Light Handle-Stem, of which the following is a specification, reference being had to the accompanying drawing, forming part thereof.

Figure 1 is a rear view of the handle stem, incorporated in a complete spotlight, showing our new design.

Fig. 2 is a side elevation thereof.

The essential feature of our design consists in providing the handle stem of the

type of spotlight illustrated in the drawings, with an open bayonet slot, and mounting on the switch plug a cap spaced adjacent the end of the handle stem.

We claim:

The ornamental design for a spot-light handle stem, substantially as described and shown.

Signed at Santa Ana, California, this 31st day of December, 1919.
